US0D1003355S

(12) **United States Design Patent** (10) **Patent No.:** **US D1,003,355 S**
(45) **Date of Patent:** **** Oct. 31, 2023**

(54) **TOSS TRAINER**

(71) Applicant: **P&P IMPORTS LLC**, Irvine, CA (US)

(72) Inventors: **Peter Engler**, Newport Beach, CA (US); **Peter Tanoury**, Newport Beach, CA (US)

(**) Term: **15 Years**

(21) Appl. No.: **29/845,833**

(22) Filed: **Jul. 11, 2022**

Related U.S. Application Data

(63) Continuation of application No. 29/752,069, filed on Sep. 24, 2020, now Pat. No. Des. 960,985, which is a continuation of application No. 29/667,739, filed on Oct. 24, 2018, now Pat. No. Des. 900,933.

Primary Examiner — Mehri F Bajoul

CLAIM

The ornamental design for a toss trainer, as shown and described.

DESCRIPTION

FIG. 1 is a front perspective view of a toss trainer showing our new claimed design;

FIG. 2 is a back perspective view thereof;

FIG. 3 is a front elevational view thereof;

FIG. 4 is a back elevational view thereof;

FIG. 5 is a top plan view thereof;

FIG. 6 is a bottom plan view thereof;

FIG. 7 is a left-side elevational view thereof; and,

FIG. 8 is a right-side elevational view thereof.

The broken lines in the figures show portions of the toss trainer that form no part of the claimed design.

1 Claim, 6 Drawing Sheets
